UNITED STATES PATENT OFFICE.

ELIJAH C. RINNER, OF COSHOCTON, OHIO.

PAPER-CORRUGATOR.

1,022,002.

Specification of Letters Patent.

Patented Apr. 2, 1912.

Application filed April 29, 1911. Serial No. 624,236.

To all whom it may concern:

Be it known that I, ELIJAH C. RINNER, citizen of the United States, residing at Coshocton, in the county of Coshocton and State of Ohio, have invented certain new and useful Improvements in Paper-Corrugators, of which the following is a specification.

My invention relates to that class of machines designed for corrugating "straw-board" paper from which corrugated paper and pasteboard is commonly formed, and the invention has for its primary object the provision of a very simple, effective and easily operated mechanism by which one layer of paper or board may be corrugated and an outer facing applied thereto.

Another object of the invention is to provide means whereby the corrugating and pressing rolls may be adjusted toward or from each other to secure more or less pressure against the paper being treated.

A still further object is the provision of means whereby the paper may be stripped from the upper corrugating roll, carried down between the second corrugating roll and the paste-applying roll and be stripped from the paste-applying roll and held so smoothly upon the corrugating roll that the paste will be applied equally over its whole area.

A further object is to provide means whereby the paste may be easily applied to the paste-applying roll so that it shall be evenly applied to the corrugated paper.

Other minor objects of the invention will appear in the course of the following description.

My invention is illustrated in the accompanying drawings wherein:

Figure 1 is a front elevation of a machine embodying my improvements. Fig. 2 is a side elevation thereof. Fig. 3 is a section on the line 3—3 of Fig. 1. Fig. 4 is a detail sectional view of the corrugating rolls, illustrating the action of one of the strippers.

Corresponding and like parts are referred to in the following description and indicated in all the views of the accompanying drawing by the same reference characters.

My improved mechanism includes oppositely disposed supporting standards 2 which may be formed in any desired manner and which are spaced from each other and held in proper engagement with each other by transversely extending beams and

tie rods, these supporting standards being spaced from each other a distance equal to the length of the corrugating rolls and the bearings therefor.

Each standard 2 is provided with a relatively fixed journal box for supporting a corrugating roll and with shiftable journal boxes above and below the fixed journal box for supporting the uppermost and lowermost rolls, respectively. In detail, each standard is formed with guides 3 formed by vertically slotting the standards within which guides are shiftably mounted the journal boxes 4, 5 and 6. The journal box 4 is rigidly engaged with the standards in any adjusted position by means of the set screws 4^a, these set screws permitting the journal box 4 to be adjusted up or down upon the standards.

The uppermost journal box 5 is supported upon the journal box 4 by means of adjusting screws 7 and this journal box 5 may be forced downward toward the journal box 4 by means of the adjusting screw 8 which extends through the upper end of the standard. By rotating this screw 8 in a reverse direction and rotating the screw 7, the pressure between the uppermost and the middle corrugating rolls may be adjusted.

The lowermost journal box 6 is likewise adjusted toward or from the middle journal box by means of an adjusting screw 8^a which passes through a transverse web 9 extending across the space between the guides 4. Adjusting screws 7^a are also interposed between the journal box 6 and the box 4. Thus the pressure between the rolls supported upon the journal boxes 4 and 6 may be properly adjusted. It will be seen that this adjustment is positive and that the pressure between the rolls supported by the journal boxes may be very delicately adjusted. These journal boxes may be made in any suitable manner and support the shafts 9, 10 and 11 of the upper corrugating rolls and pressing rolls, respectively.

Mounted upon the shaft 9 is the uppermost corrugating roll 12 which is formed with transversely extending corrugations. The shaft 10 supports the lower corrugating roll 13 which is also provided with longitudinally extending corrugations designed to mesh with the corrugations on the roll 12. The shaft 11 supports a roll 14 which has a smooth exterior face and is designed as a pressing roll. All of these rolls,

12, 13 and 14 are hollow and are connected to suitable means whereby the steam may be conducted into the interior of the rolls for the purpose of keeping the rolls hot. I have not shown any special construction for this purpose inasmuch as this mechanism is well known in the art. The roll 12 is provided with circumferentially extending grooves 15 which are relatively deep.

Mounted upon the supports 2 is the paste trough 16. This trough extends toward the roll 13 and is upwardly bent as at 17 at its forward edge, this upwardly bent side 17 of the paste trough extending upward between the roll 13 and a paste-applying roller 18. This paste-applying roller is mounted in any suitable manner upon the trough 16 and dips into the trough.

The roller 18 is formed with a plurality of circumferential grooves 19 which align with the grooves 15 on the roll 12. The faces of the rolls 13 and 18 are in approximate contact. Mounted rearward of the roll 18 is the spreading roll 20 which is designed to distribute paste or like adhesive material over the surface of the roll 18 and to prevent the roll 18 carrying too great an amount of paste.

Mounted on a transverse bar 21 extending between the standards are a plurality of strippers 22, these strippers consisting of wires, each at one end coiled around the rod 21, then extending rearward and downward between the rolls 12 and 13 and in the grooves 15. The grooves in these rolls 12 and 13 are slightly deeper than the diameter of the wire used to form the stripping fingers or strippers. These wire fingers or strippers extend rearward and downward over the roll 13 and downward between the roll 13 and the paste-applying roll 18 and are attached at their lower ends to a transverse rod or bar 23 which extends between the standards immediately in front of the paste trough 16. The downward extensions of the stripping fingers or wires 22 act to hold the paper passing over the corrugating roll 13 in close contact with the roll 13 and thus hold the paper relatively flat so that the paste-applying roll will contact evenly over the whole surface of the paper with the crests or ridges of the corrugations, thus applying the paste uniformly to these crests or ridges.

It is to be noted that the stripping wires 22 do not have as great a curvature as the rolls 12 and 13. It is to be noted that the upper ends of the stripping wires 22 are curved to conform to the curvature of the roll 12 and that the lower ends of the stripping wires or fingers 22 correspond to the curvature of the roll 13 but do not touch the roll 13 but rest within the grooves 19 of the paste-applying roll 18. These stripping fingers or wires first act to strip the

paper after it is corrugated from the uppermost corrugating roll and guide the paper over the lower corrugating roll, thus preventing the paper sticking to the upper corrugating roll and any tendency of the paper to follow the upper roll. After the paper has passed onto the lower corrugating roll, the said fingers act to hold the corrugated paper to the roll 13 and also act to keep the paper from rumpling or becoming wrinkled and thus permit the paste-applying roll to apply paste uniformly to the crests of the corrugations.

Supported upon arms 23 projecting from the standards 2 is the paper reel shaft 24. This reel shaft is designed to be passed through the center of a roll of paper or cardboard to be corrugated. This shaft is screw threaded at opposite ends as at 25 and provided with centering chucks 26. These centering chucks have screw threaded nuts 27 which engage with the screw threaded portion 25 whereby the chucks may be adjusted along the shaft 24 so as to accommodate rolls of paper having different widths.

The paper from the roll 28 supported upon the shaft 24 is carried over a guide roller 29 which extends along the front of the machine, this guide roller being so located that the sheet of paper 30 passing thereover is supported below the transverse rod 21 supporting the stripping fingers and in such position that the paper may move easily between the corrugating rolls 12 and 13.

It will be seen from Figs. 2 and 3 that the paper 30 passes beneath the forward ends of the stripping fingers 22 and that as the paper passes out of the stripping rolls, it will still be beneath said fingers and that said fingers will prevent the paper after it is corrugated from sticking to and following the path of the upper corrugating roll 12 and will guide the paper downward over the corrugating roll 13. The sheet of paper 30 passes over and around the corrugating roll 13 and there comes in contact with a paste applying roller 18. Thus paste is applied to the surface of the paper.

The sheet 31 comes from a roll 32 mounted upon a spindle or shaft 33 supported in bearings 34 at the base of the standards and below the roll of paper 30. The sheet of paper 31 passes over the roll 32 forward and around a guide roller 35, and from thence passes rearward and over the pressing roll 14 whose face is smooth.

The sheet of paper 31 after it passes the paste applying roller 18 passes between the roller 14 and the roll 13. The sheet 31 is then carried upward and forward over the roll 14 and into contact with the under face of the corrugated paper 30 as it moves downward and forward over the roll 13.

The two sheets of paper 30 and 31 are then carried forward and between pressing platens or other drying and pressing devices 36. These pressing platens are not shown in detail as they may be made in any suitable manner and are well known in the art.

It will be seen that with the construction above described proper pressure is secured between the corrugating rolls 12 and 13 by adjusting the screw 8, while proper pressure is secured between the rolls 13 and 14 by adjusting the screw 8*. The pressure on the roll 12 is necessary in order to secure a proper corrugation of the paper, while the pressure on the bottom roll is necessary in order to get a proper adhesion of the plain paper to the corrugated paper. Proper tensioning devices are of course provided to secure a proper tension upon the paper as it passes through the corrugator, but I have not thought it necessary to describe these tensioning devices as they are well known in the art. I have provided for this purpose, however, a slotted casting 37 which is mounted upon the upper end of one of the standards 2 and beneath and rearward of the shaft or spindle 20 upon which the roll is mounted. This casting is provided with two parallel horizontally disposed slots 38.

30 A rope or other like flexible connection knotted at opposite ends may be connected to this casting and passed around the spindle 24 or a pulley mounted thereon, and thus resist the rotation of the roll 28 to a sufficient degree to place a proper tension upon the paper.

Steam is carried into the several rolls by means of steam pipes 39 which are connected to these rolls in a manner well known in the art and therefore requiring no description.

While I do not wish to limit myself to any specific means for rotating the several rolls, I have shown for this purpose the roll 13 as being mounted on a shaft 10 which projects out beyond one of the supporting standards and is provided with a gear wheel 40. This meshes with a gear wheel 41 of the same diameter upon the shaft 9 of the roll 12 and 45 also meshes with a gear wheel 42 upon the shaft 11 of the roll 14. In order to rotate the paste-applying rolls, I provide the shaft of the roll 18 with a gear wheel 43 which meshes with the gear wheel 42. Either one 50 of the rolls 18 or 20 may be positively driven, however, and the other roll be rotated by frictional contact with the driven roll. The shaft 10 is preferably provided with a gear wheel 44 by which power may 55 be applied to the train of rolls in any suitable manner.

What I claim is:

1. A paper corrugating machine, including a first named corrugating roll, a coacting corrugating roll disposed on one side of

the fixed roll and movable toward or from the same, a pressing roll mounted diametrically opposite to the movable corrugating roll and coacting with the fixed corrugating roll, said pressing roll being shiftable toward or from the fixed roll, adjustable spacing means disposed between the rolls and positively holding them spaced apart and means for directing a sheet of fabric between the corrugating rolls and between the pressing roll and the fixed roll and for directing a sheet of fabric between the pressing roll and the first named sheet.

2. A paper corrugating machine, including an adjustable corrugating roll, a movable corrugating roll mounted on one side of the first named adjustable roll and having means whereby it may be positively adjusted toward or from the first named roll, a smooth pressing roll on the other side of the first named roll and adjustable toward or from the first named roll, adjustable means for positively spacing the rolls from each other, a paste-applying roller mounted adjacent to the first named corrugating roll, means for directing a sheet of fabric between the corrugating roll and the paste-applying roller and carrying said fabric between the pressing roll and the first named corrugating roll, and means for directing a sheet of fabric between the two corrugating rollers and between the first named corrugating roll and the first named sheet of fabric.

3. In paper corrugating machinery, a corrugating roll mounted in slidably adjustable journals, a superposed corrugating roll mounted in journals shiftable toward or from the journals of the first named roll, a pressing roll below the first named roll and mounted in journals shiftable toward and from said first named roll, adjustable means interposed between the said journals for positively and adjustably spacing the journals from each other, means for forcing the superposed corrugating roll and the pressing roll toward the first named roll, means for directing a sheet of paper between the corrugating rolls then over the first named corrugating roll and between said roll and the pressing roll, means for directing a sheet of paper over the pressing roll and between said roll and the first named sheet of paper, and means for applying paste to the sheet as it passes over the corrugating roll.

4. A paper corrugating machine, including upper and lower rolls and an intermediate roll, means for vertically adjusting the intermediate roll, means for independently adjusting the upper roll relatively to the intermediate roll, and means for independently adjusting the lower roll toward and from the intermediate roll.

5. A paper corrugating machine, including side standards, each vertically slotted,

an upper corrugating roll, a lower pressing roll, and an intermediate corrugating roll between the pressing roll and the first named corrugating roll, all of said rolls being mounted in journal bearings sliding in the vertical slots of the standards, means for adjustably holding the journal bearings of the intermediate corrugating roll in fixed relation to the standards, means for forcing the upper corrugating roll toward the intermediate corrugating roll, means for forcing the pressing roll toward the intermediate corrugating roll, and adjustable means disposed between the journal bearings of the several rolls for positively spacing the upper corrugating roll and the lower pressing roll with relation to the intermediate corrugating roll.

6. In a paper corrugating machine, opposed side standards, each formed with vertical guides, a corrugating roll mounted in journals slidingly engaged with said guides, means for holding the said journals in fixed relation to the slides, a superposed corrugating roll mounted in journals shiftable toward or from the first named roll, a pressing roll mounted in journals below the first named roll, said journals being shiftable toward or from the journals of the first named roll, adjusting screws for positively moving the journals of the uppermost corrugating roll and of the pressing roll toward or from the lower corrugating roll, and adjusting screws interposed between the journals of the lowermost corrugating roll and the upper corrugating roll and between said first named journals and the journals of the pressing roll.

7. A paper corrugating machine, including two superposed corrugating rolls, each having circumferential grooves, said grooves alining with each other, a paste-applying roll mounted opposite to and in approximate contact with one of said corrugating rolls, and a plurality of stripping fingers supported at opposite ends extending through between the corrugating rolls and disposed in the grooves thereof and then extending between the paste-applying roll and the adjacent corrugating roll and disposed in the grooves thereof.

8. A paper corrugating machine, including a lower corrugating roll and a superposed corrugating roll, each roll having a plurality of circumferential grooves, said grooves alining, a paste-applying roll contacting with the lower corrugating roll and having circumferential grooves alining with the grooves therein, a transverse support located opposite to the upper corrugating roll and on one side of the machine, a transverse support located opposite to the lower corrugating roll and below the point of contact between the paste-applying roll and the corrugating roll, and a plurality of stripping wires attached to said supports extending through in said grooves between the upper and lower corrugating rolls and between the lower corrugating roll and the paste-applying roll.

In testimony whereof, I affix my signature in presence of two witnesses.

ELIJAH C. RINNER. [L. S.]
